FIG ____ 1

FIG ____ 2

FIGURE 1 is a perspective view of a bird feeder, showing my new design.

FIGURE 2 is a vertical cross-sectional view thereof partly in full, taken through the center of the feeder, on a reduced scale.

The design is circular throughout its cross-section and is provided with four cylindrical food-containing compartments uniformly disposed around the circumference thereof, as is best shown in FIGURE 2.

I claim:

The ornamental design for a bird feeder, as shown and described.
